(57) **CLAIM**

The ornamental design for a robotic snow plow, as shown and described.

DESCRIPTION

FIG. 1 is a left front perspective view of a robotic snow plow showing my new design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a bottom plan view thereof; and,

FIG. 7 is a top plan view thereof.

1 Claim, 7 Drawing Sheets**FIG. 1**

FIG. 2

FIG. 3

FIG. 4

FIG. 5

FIG. 6

FIG. 7
